Patented March 7, 1905.

UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 37,363, dated March 7, 1905.

Application filed January 28, 1905. Serial No. 243,151. Term of patent 7 years.

To all whom it may concern:

Be it known that I, CHARLES J. AHRENFELDT, a citizen of the United States, and a resident of New York city, in the county of New York and State of New York, have invented a certain new, original, and ornamental Design for a Plate or Similar Article, of which the following is a specification.

In the accompanying drawing the figure is
10 a plan showing the design on the plate.

What I claim is—

The ornamental design for a plate or similar article as shown.

CHARLES J. AHRENFELDT.
